UNITED STATES PATENT OFFICE.

GERÓNIMO CROSETTI, OF BUENOS AIRES, ARGENTINA.

LAMP.

1,385,430.

Specification of Letters Patent. Patented July 26, 1921.

Application filed November 29, 1920. Serial No. 427,015.

To all whom it may concern:

Be it known that I, GERÓNIMO CROSETTI, citizen of the Republic of Argentina, residing at 3060 Cramer street, Buenos Aires,

5 Republic of Argentina, have invented certain new and useful Improvements in Lamps, of which the following is a specification.

This invention relates to an improved 10 lamp for the production of heat and light, and has for its object the provision of a lamp adapted to burn liquid fuel, such as kerosene, naphtha, or the like, wherein no wick submerged in the liquid fuel is used and in 15 which the said fuel rises by capillarity to the burner nozzle through a tubular chamber formed between two concentric bodies.

In the practical form of construction of 20 the lamp, a pin or core is inserted into the bore of a tube, leaving between both parts a narrow tubular chamber, means being provided for the admission of the liquid fuel at the bottom of such chamber. At the top of said chamber is placed a flat strip of asbestos or other porous, permeable and in 25 combustible material which becomes saturated with the fuel and which, after being ignited, produces light and heat.

The liquid rises by capillarity within the 30 aforesaid tubular chamber and is thus fed without interruption to the piece of asbestos until the same has entirely been consumed. The liquid fuel as well as the lower part 35 of the tube and core are inclosed within a container of suitable form and material.

Kerosene and naphtha burning lamps, as 40 well as alcohol lamps are well known, but all these lamps comprise a wick holder and a cotton wick submerged within the liquid fuel which rises therein to the burner by 45 capillarity. This arrangement however, is open to several objections; for instance, the wick will harden in time and thus interfere with the rise of the liquid, besides producing an insufficient amount of light and heat, its 50 upper part burns away; moreover, the operation of such burners generally causes a disagreeable smell.

By causing the liquid to rise by capillary 55 action through the annular chamber between the core and the tube until reaching the piece of asbestos fitted in the upper end of the tube and supported partly thereby and partly upon the upper end of the core, a perfect flame is obtained, as well as a carbureted combustion, without any smell.

The piece of asbestos may be placed in position or withdrawn, at will and without any difficulty, thereby dispensing with the use of a burner, or wick holder, cotton wicks 60 and the mechanical devices required for operating or adjusting the wick.

In connection with the lamp constructed in accordance with this invention and for the purpose of regulating the flame, any 65 suitable or desired means may be employed, such as a telescoping outer sleeve applied to the capillary tube which, on being raised, will decrease the light and heating power 70 of the lamp, while increasing the same when being lowered, as will readily be understood.

The lamp according to this invention may be used for several purposes, as for lighting, with or without a shade, or for generating 75 heat in connection with stoves or kitchen ranges, to which end the device will be arranged within a suitable frame.

In order that the invention may readily be understood and carried into practice without difficulty, two of the preferred embodiments of the same have been illustrated in the accompanying drawings, wherein:

Figures 1 to 6 show an embodiment of the improved lamp, preferably for use as light producer, Fig. 1 being a side elevation, Fig. 2 a central vertical section and Fig. 3 a central vertical section of the container; Fig. 4 is a view showing the bottom member of said container, with the pin secured thereto, the container member appearing in section; Fig. 5 is a side elevation of the shade and Fig. 6, finally, shows a central section of the fuel drawing device and of the means for adjusting the flame.

In Figs. 7 to 11 a modified construction of 85 lamp in accordance with this invention is shown, Fig. 7 being a side elevation of the complete lamp; Fig. 8 shows a central vertical section of the same; Fig. 9 illustrates a detail of the flame regulating sleeve; Fig. 10 is an elevation of the capillary tube with the means for adjusting the sleeve, and Fig. 11, finally, is a perspective view of the piece 90 of asbestos.

Referring now to the first embodiment 105 shown in Figs. 1 to 6, *d* indicates the container which may be of any suitable material, provided with a plain bottom *c* having a series of recesses *f*, *f'*, *f''*, adapted to serve as feet. At the center of said bottom is af- 110 fixed by soldering or otherwise, as indicated at *a'*, the lower end of a vertical core in the

- form of a pin *a*, over which is telescoped a cylindrical tube *b*, said pin or core and tube being made of metal and being spaced from each other to produce an intermediate tubular chamber which communicates at its lower end with the interior of the chamber. The tube *b* is provided at its upper portion with a conical metal plug *h*, soldered at the inside to the surface of the tube; said plug fits in the conical ring *i*, secured by solder inside to the surface of the container at *i'*, whereby the receptacle for the liquid fuel is maintained perfectly closed, so as to avoid any risk of leakage or of the fire getting into the interior of the container.
- e* is a small, flat strip of asbestos or other porous, absorbent and incombustible material which is inserted in the upper end of the tube so as to rest horizontally upon the top of the core, the said tube being surrounded by a sleeve *m*, for the purpose of increasing or decreasing the heat or light produced by the lamp, which may be done by turning the said sleeve by means of its flange *m'*.
- The sleeve *m* is provided with a projection or finger *m*² which bears on the inclined or cam surface of the plug *h*, the sleeve *m* describing, when rotatated, a helically ascending movement, as will readily be understood.
- By raising the sleeve *m*, the flame will be reduced, and when lowering the same, the opposite will take place.
- The plug *h* and tube *b* may be withdrawn in order to enable the inner surface of the tube *b* to be thoroughly cleaned, as well as the outer surface of the pin *a*, thereby avoiding any interference with the free capillary rise of the liquid fuel. The conical orifice will thus have been opened at *i*, and the liquid fuel may be introduced through the same. After charging the container *d*, the plug *h* and tube *b* are again placed in position. The liquid will rise by capillary action through the tubular chamber between the said tube *b* and the pin *a* and arrive at the piece of asbestos *e* which will absorb the necessary amount; and after being ignited, the said piece of asbestos will continually be fed with fuel until all of the liquid contained within the receptacle *d* has been consumed. The container *d* is suitably fastened at its bottom to the member *c*, and is also provided with a suitable handle to facilitate handling of the lamp.
- If desired, the lamp may be provided with a shade *g*, to which is affixed a pin *g'*, rolled or wound at one of its ends so as to form a handle and extended at *g''*, at the other end, for insertion in a small tube *h* soldered to the container.
- In the modified construction shown in Figs. 7 to 11, the capillary tube, its pin or core, the chamber between the tube and core, the piece of asbestos and the means for adjusting the flame, are all of rectangular

shape in cross section, instead of being cylindrical as in Figs. 1 to 6. Besides, the flame adjusting tube is operated in this case by means of a rack and a pinion, as will later be described. *r* indicates the capillary pin or core, of rectangular cross section, soldered at *r'* to the bottom of the container destined to hold the liquid fuel; and on the said core is telescoped a tube of rectangular section *q*, on top of both of which parts is supported the piece of asbestos *u*, also of rectangular shape. *n* is the sleeve for adjusting the flame, of rectangular section, placed outside the tube *q* and having secured to one of its sides a rack *n'*. This rack engages with a toothed pinion *n*², secured to the axle *n*³, mounted in bearings *p* and *p'* formed in the arms of a forked bracket *p*² which is soldered or otherwise secured at its lower end at *q'* to the adjacent side of the capillary tube *q*; on one end of said axle is mounted an operating disk *o*, as clearly shown in the drawings. *s* indicates the cap of the container and *s'* is a locking or safety ring, to prevent leakage or fire.

It will be understood that the operation of this lamp is similar to that described in connection with the former embodiment, so that a detailed description thereof is deemed unnecessary.

Having now described my said invention, I declare that what I claim and desire to secure by Letters Patent, is:

1. A lamp, comprising a liquid fuel receptacle embodying a bottom member; a vertical core secured at its lower end to the bottom member and projecting upwardly beyond said receptacle; an open-ended vertical tube fitting over said core but spaced therefrom to produce an intermediate tubular chamber therebetween which communicates at its lower end with the interior of the fuel receptacle; and a piece of absorbent, substantially non-combustible material fitting in the upper end of the tube and to which the fuel is fed by capillarity through said chamber.

2. A lamp, comprising a liquid fuel receptacle embodying a bottom member; a vertical core secured at its lower end to the bottom member and projecting upwardly beyond said receptacle; an open-ended vertical tube fitting over said core but spaced therefrom to produce an intermediate tubular chamber therebetween which communicates at its lower end with the interior of the fuel receptacle; a piece of absorbent, substantially non-combustible material fitting in the upper end of the tube and to which the fuel is fed by capillarity through said chamber; and a vertically slideable sleeve fitting over the upper portion of said tube to regulate the flame.

3. A lamp, comprising a liquid fuel receptacle embodying a bottom member; a ver-

- tical core secured at its lower end to the bottom member and projecting upwardly beyond said receptacle; an open-ended vertical tube fitting over said core but spaced therefrom to produce an intermediate tubular chamber therebetween which communicates at its lower end with the interior of the fuel receptacle; a piece of absorbent, substantially non-combustible material fitting in the top of the tube and to which the fuel is fed by capillarity through said chamber; a conical plug secured to the tube and fitting removably in said ring to prevent leakage of the fuel and access of the flame to the interior of said fuel receptacle, said plug having a cam surface; and a regulating sleeve for the flame rotatably fitted on said tube and having a projection for coöperation with said cam surface to raise or lower the sleeve during its rotation.
4. A lamp comprising a liquid fuel receptacle embodying a bottom member; a solid metal, vertical core secured at its lower end to the bottom member and projecting upwardly beyond said receptacle; an open-ended, imperforate vertical metal tube fitting over said core but spaced therefrom to produce an intermediate tubular chamber therebetween which communicates at its lower end with the interior of the fuel receptacle; and a piece of absorbent, substantially non-combustible material fitting in the upper end of the tube and to which the fuel is fed by capillarity through said chamber.
5. A lamp, as claimed in claim 1, in which the piece of absorbent material consists of a small, flat, horizontal strip of asbestos resting partly in the top of the tube and on the core.
6. A lamp, comprising a liquid fuel receptacle embodying a bottom member; a conical ring secured at its upper edge within said receptacle to the inner surface thereof; a vertical core secured at its lower end to said bottom member and projecting upwardly through said ring beyond said receptacle; an open-ended vertical tube removably fitting over said core but spaced therefrom to produce an intermediate tubular chamber therebetween which communicates at its lower end with the interior of the fuel receptacle; a piece of absorbent, substantially non-combustible material fitting in the top of the tube and to which the fuel is fed by capillarity through said chamber; and a conical plug secured to the tube and fitting removably in said ring to prevent leakage of the fuel and access of the flame to the interior of said fuel receptacle.
7. A lamp, comprising a liquid fuel receptacle embodying a bottom member; a conical ring secured at its upper edge within said receptacle to the inner surface thereof; a vertical core secured at its lower end to said bottom member and projecting upwardly through said ring beyond said receptacle; an open-ended vertical tube removably fit-
- ting over said core but spaced therefrom to produce an intermediate tubular chamber therebetween which communicates at its lower end with the interior of the fuel receptacle; a piece of absorbent, substantially non-combustible material fitting in the top of the tube and to which the fuel is fed by capillarity through said chamber; a conical plug secured to the tube and fitting removably in said ring to prevent leakage of the fuel and access of the flame to the interior of said fuel receptacle, said plug having a cam surface; and a regulating sleeve for the flame rotatably fitted on said tube and having a projection for coöperation with said cam surface to raise or lower the sleeve during its rotation.
8. A lamp, comprising a liquid fuel receptacle embodying a bottom member; a vertical core secured at its lower end to the bottom member and projecting upwardly beyond said receptacle; an open-ended vertical tube fitting over said core but spaced therefrom to produce an intermediate tubular chamber therebetween which communicates at its lower end with the interior of the fuel receptacle; a piece of absorbent, substantially non-combustible material fitting in the top of the tube and to which the fuel is fed by capillarity through said chamber; a flame-regulating element slidably and rotatably mounted on the upper portion of the tube; and means coöperative with said regulating element to alternatively raise or lower it during its rotation.
9. A lamp, comprising a liquid fuel receptacle embodying a bottom member; a vertical core secured at its lower end to the bottom member and projecting upwardly beyond said receptacle; an open-ended vertical tube fitting over said core but spaced therefrom to produce an intermediate tubular chamber therebetween which communicates at its lower end with the interior of the fuel receptacle; a piece of absorbent, substantially non-combustible material fitting in the top of the tube and to which the fuel is fed by capillarity through said chamber; a member secured to said tube and provided with an inclined surface; and a flame-regulating sleeve slidably and rotatably mounted on the tube and having a projection coöperative with said inclined surface to alternatively raise or lower said sleeve during its rotation.

In testimony whereof I affix my signature
GERÓNIMO CROSETTI.
